US00D800123S

(12) **United States Design Patent** (10) **Patent No.:** **US D800,123 S**
(45) **Date of Patent:** **** Oct. 17, 2017**

(54) **SCANNER**

(71) Applicant: **BROTHER INDUSTRIES, LTD.**,
Nagoya-shi, Aichi-ken (JP)

(72) Inventors: **Kazuhis Tashima**, Nagoya (JP);
Yukihiko Sato, Nagoya (JP)

(73) Assignee: **BROTHER INDUSTRIES, LTD.**,
Nagoya-shi (JP)

(**) Term: **15 Years**

(21) Appl. No.: **29/571,094**

(22) Filed: **Jul. 14, 2016**

(30) **Foreign Application Priority Data**

Jan. 14, 2016 (JP) 2016-570

CLAIM

The ornamental design for a scanner, as shown and described.

DESCRIPTION

FIG. 1 is a perspective view of a scanner;
FIG. 2 is a front view thereof;
FIG. 3 is a top view thereof;
FIG. 4 is a right-side view thereof;
FIG. 5 is a left-side view thereof;
FIG. 6 is a rear view thereof; and,
FIG. 7 is a bottom view thereof.

The broken lines depict environmental subject matter only and form no part of the claimed design. The dot-dash chain lines depict a boundary of the claimed subject matter and form no part of the claimed design.

1 Claim, 6 Drawing Sheets
